POST EXTRACTOR
Bill A. Harmon, 1821 N. 35th St.,
Phoenix, Ariz. 85008
Filed Sept. 9, 1966, Ser. No. 578,366
6 Claims. (Cl. 254—30)

ABSTRACT OF THE DISCLOSURE

A post extractor having a wheel supported truck provided with an upstanding frame carrying a post engaging guide adapted to guide posts while pulled upwardly by a chain or cable retracting device, such that the posts will be straddled by the truck of the extractor, and may extend above the guide and above the frame without interference therewith in order that the posts may be extracted from the ground and pulled directly upwardly.

This invention relates to a post extractor, and more particularly, to a post extractor for pulling fence posts, or the like, and extracting them from the ground.

It has been a problem to provide a simple lightweight manually operable fence post extractor, which may be used by contractors, and others, for the purpose of extracting fence posts, or the like, from the ground.

Large machines have been used for this purpose, and in many instances, such large machines which fail to pull the posts in a direction parallel to its axis and align with the axis of the posts, tend to bend these posts and create great difficulty in extracting the posts from the ground.

When a force is applied to a post, during the extraction thereof from the ground, and such force is at an angle to the axis of the post, not only tends to bend the post, but tends to bind the post in the ground. This is particularly true, where the lower ends of posts are set in concrete and the concrete is fixed to the posts. The large area of the concrete in the ground, not only tends to become bound by any force applied laterally of the axis of posts, but it tends to resist such force and cause the posts to be bent or damaged.

Large machines are not readily usable in some crowded areas in which fences are installed, and therefore, the need for a compact lightweight and powerful fence post extractor has been apparent.

It has also been obvious that the digging of fence posts requires a lot of labor and that any attempt to pull a fence post by usual manual devices may fail, either due to the force required, or due to a poor application of force not axially aligned with the posts.

Accordingly, it is an object of the present invention to provide a very simple, compact, lightweight, portable fence post extractor which may be used in restricted or limited areas, and which very efficiently applies powerful forces to posts parallel to and aligned with the axis of the posts, so that they are most efficiently extracted from the earth without being damaged.

Another object of the invention is to provide a post extractor having a wheel support carriage, including horizontally disposed members which extend forwardly from a cross member, and which provides for a free unobstructed area between the horizontal members for straddling a post to be extracted, and wherein a vertical member is provided with a forwardly extending post guide adapted to bear on one side of the post, so that when a tensioning device connected to an upstanding member of the extractor applies a force to the post at a slight angle to the axis thereof, the post guide bears on the post and holds it in a vertical position, thereby causing the resultant of the force to be vertical, since the wheel supported frame of the extractor may move to align the

2

post guide with the post and thereby cause a resultant force of the extractor to be aligned with the axis of the post.

Another object of the invention is to provide a post extractor of very simple construction, employing a simple frame supported on wheels, including a cantilever or forwardly extending post guide and the simple manually operable come-a-long, all of which provides for simplicity, compactness, power and efficiency in the extraction of posts from the ground.

Another object of the invention is to provide a very simple post extractor which can be operated by a single man during the extraction of posts from the ground, even though such posts are secured to the ground by large concrete footings.

Further objects and advantages of the invention may be apparent from the following specification, appended claims and accompanying drawings, in which:

FIG. 1 is a side elevational view of a post extraction, in accordance with the present invention, showing the post extractor engaged with a substantially vertical post, the base of which is set in concrete and illustrating portions of the invention broken away and in section to amplify the illustration; and

FIG. 2 is a plan sectional view taken from the line 2—2 of FIG. 1.

The post extractor of the present invention, as shown in FIGS. 1 and 2 of the drawings, is provided with a frame 10 having a rearward portion 12 and a forward portion 14. The frame is composed of two pairs of horizontally disposed members 16 and 18 interconnected by a cross member 20. The horizontal members 16 and 18 are supported by wheels 22 and 24 and 26 and 28, respectively. The wheels 24 and 28 being on the forward free ends 30 and 32 of the horizontally disposed members 16 and 18, respectively.

It will be seen that the free ends 30 and 32 are supported by the wheels 24 and 28 and provide an unobstructed area therebetween and forwardly of the cross member 20.

The wheels 22 and 26 support the frame rearwardly of the cross member 20. Upstanding members 34 and 35 extend upwardly from the members 16 and 18, respectively, as shown best in FIG. 1 of the drawings. Secured by welding or otherwise to these upstanding members 34 and 35 by a cross member 37, is a forwardly directed post guide 36 having a post engaging roller 38 rotatably mounted thereon, said roller being rotatable about an axle 40, carried by the post guide 36. The post guide 36 is also fixed to a brace 47 to be hereinafter described. As shown in FIGS. 1 and 2 of the drawings, this roller 38 is adapted to bear against the side 46 of a post 48, being extracted from the ground. The post, as shown in FIG. 1, is secured in a concrete footing 50 and the extraction of this post can be most readily accomplished by pulling the post vertically and parallel with its axis.

A chain 52 wrapped at 54 around the post 48, extends upwardly and is engaged by a hook 56 of a chain 58 powered by a manually operable come-a-long 60 having its frame secured by a hook 62 to a cross member 64 at the upper end of the upstanding members 34 and 35.

A brace 47 interconnects the cross members 20 and 64 to brace the upstanding members 34 and 35 and the post guide 36.

In operation, the chain 54 is wrapped around the post 48 and tension is applied to the chain 58 and chain 52 by the manually operable come-a-long 60. During this application of tension force, compression is created in the upstanding members 34 and 35 and tension is applied to the post 48. It will be understood, however, that the wheels 22, 24, 26 and 28 permit the frame to move in the direction of an arrow A in FIG. 1 of the drawings, until

the roller 38 of the post guide 36 engages the side 46 of the post 48. Further tension causes the post 48 to be pulled vertically due to the fact, that the post guide, including the roller 38, translates the angular force of the chains 52 and 58 into a vertical resultant parallel to the vertical axis of the post 48 and, consequently, the forces tend to move the frame 10 on the wheels 22, 24, 26 and 28 into a position, wherein the unrestricted area between the horizontal members 16 and 18 is occupied by the post 48 and it is aligned vertically by means of the roller 38 on the post guide 36.

Continued action of the come-a-long 60 operated manually by a handle 66 will apply vertical force in connection with the post 48 and extract it from the ground, together with its concrete footing 50.

It will be obvious to those skilled in the art that various modifications of the present invention may be resorted to in a manner limited only by a just interpretation of the following claims.

I claim:

1. In a post extractor, the combination of: a frame having forward and rearward ends; a pair of spaced horizontally disposed members; a cross member interconnecting said horizontally disposed members; said horizontally disposed members having free ends projecting toward the forward end of said frame and forwardly from said cross member and thereby providing an unobstructed area extending between said horizontally disposed members and to said free end thereof; first wheels supporting said free ends; second wheels supporting said frame rearwardly relative to said cross member; an upstanding member supported on said cross member and extending upwardly therefrom; a post guide means connected to said upstanding member and projected forwardly and adapted to form a bearing for a post located in said unobstructed area; and means for applying a compressive load to said upstanding member and an upward force to said post, causing it to bear on said post guide to be extracted vertically from the earth, said frame unobstructed above said guide means to permit a post freely to move upwardly as it is extracted vertically from the earth, and while an uppermost portion of said post extends freely above an uppermost portion of said frame.

2. In a post extractor, the combination of: a frame having forward and rearward ends; a pair of spaced horizontally disposed members; a cross member interconnecting said horizontally disposed members; said horizontally disposed members having free ends projecting toward the forward end of said frame and forwardly from said cross member and thereby providing an unobstructed area extending between said horizontally disposed mem-

bers and to said free end thereof; first wheels supporting said free ends; second wheels supporting said frame rearwardly relative to said cross member; an upstanding member supported on said cross member and extending upwardly therefrom; a post guide means connected to said upstanding member and projected forwardly and adapted to form a bearing for a post located in said unobstructed area; and means for applying a compressive load to said upstanding member and an upward force to said post, causing it to bear on said post guide means to be extracted vertically from the earth, said post guide means is provided with a roller adapted to bear on the side of said

3. The invention, as defined in claim 2, wherein: operation of said last mentioned means causes said wheels to roll on the ground and to align said frame in such a position, that said post guide means bears on the side of said post to thereby guide said post vertically during its extraction from the earth, said last mentioned means comprising a chain and come-a-long.

4. The invention, as defined in claim 1, wherein: said last mentioned means, includes tensioning means coupled to said upstanding member and said post and applying force to said post at an acute angle thereto, while said guide means holds said post in a vertical position.

5. The invention, as defined in claim 1, wherein: said last mentioned means, includes tensioning means coupled to said upstanding member and said post and applying force to said post at an acute angle thereto, while said guide means holds said post in a vertical position; said tensioning means being a manually operable come-a-long.

6. The invention, as defined in claim 1, wherein: said post guide means is provided with a post engaging roller having a horizontally disposed axis of rotation; a chain adapted to be secured to a post below said roller and adapted to extend upwardly adjacent said roller at an angle to said upstanding member, said chain adapted to be connected to said last mentioned means for creating tension therein and for extracting said post from the ground.
